(57) **CLAIM**

The ornamental design for lavatory module, as shown and described.

DESCRIPTION

FIG. 1 is a front perspective view of the claimed design; FIG. 2 is a front elevation view of the claimed design; FIG. 3 is a cross-sectional view of a right side of the claimed design as taken along 3-3 in FIG. 2;

FIG. 4 is cross-sectional view of a left side of the claimed design along 4-4 in FIG. 2; and,

FIG. 5 is a cross-sectional downward facing view of the claimed design along 5-5 in FIG. 2.

The broken line representations in the figures depict portions of the article that form no part of the claimed design.

1 Claim, 5 Drawing Sheets
